GOLF STROKE TEACHING MACHINE

William E. Beil and Floyd Farley, Oklahoma City, Okla.

Application September 2, 1941; Serial No. 409,168

11 Claims. (Cl. 273—35).

This invention relates to a device for mechanically teaching golf strokes or swings, and it is believed to be the first device of its class which holds, guides, and controls the movement of a golf club while leaving a player comparatively free to swing the golf club, with arms and body unhampered.

It is the chief object of this invention to provide a device which allows a player to grasp and swing the golf club in the usual manner, yet which guides the travel of the club through what is generally conceded by professional players to be a perfect "swing," so that the learning player is forced to recognize the faults both in his back swing and in his downswing. The device is so constructed that it forces a learning right handed player to take a relatively slow back swing, to keep his left arm relatively straight all the way to the top of the back swing, to delay the break of the wrists until the proper time, near the top of the back swing, to keep the right elbow near the body, to pivot the body properly during the back swing, and above all to recognize the proper relative positions between his hands and club head at each point of the back swing. As is well known to professionals and other expert golf players, the club head and the player's hands respectively travel through different areas or paths, as well as through different respective but unchanging planes during the back swing and the downswing. Accordingly, this invention also positively guides the travel of both the club head and the hands in the proper respective paths and planes during the downswing, even to the point of notifying the learning player when to bring the wrist muscles into play, just before the club head hits the ball. Also, the machine encourages, in fact almost forces, a full "follow through" after the club head has passed its point of impact with the ball.

In addition to guiding the club head as well as the player's hands in the proper paths during the complete swing, the invention forces the club head to travel in its proper individual plane during the complete swing, forces the player's hands to travel in their proper individual plane during the swing, and is so constructed that it forces proper pronation of the hands and club during the backswing, and proper compensation or breaking of the wrists at the top of the backswing. At the top of the backswing the player's hands and the club coincide with the line of intersection of the two planes in which the player's hands and the club head have respectively traveled to reach the top of the swing. This is con-

sidered the ideal club and hand position for starting the downswing. During the downswing the device forces both the club head and the player's hands to return through the same respective planes in which they traveled to reach the top of the backswing. Those familiar with the art will clearly understand the important distinction between the two planes in which the club head and hands respectively travel during a swing, and the paths in which the club head and hands travel within their respective intersecting planes.

Another object of the invention is to provide a device of this class, the use of which may be coin controlled, so that a player desiring to learn the defects of his normal swing may insert a coin, thus freeing the machine for a predetermined number of complete teaching swings.

Still another object is to provide a machine of this class which is adjustable to suit players of varying height, and which is so constructed that the golf stroke which it teaches may be changed without rebuilding the machine.

The details in the construction of a preferred form of our invention, together with other objects attending its production, will be better understood from the following description when read in connection with the accompanying drawings, which are chosen for illustrative purposes only, and in which

Fig. 1 is an assembled view of one embodiment of the invention, in perspective, with the club holding and guiding mechanism in normal or locked position;

Fig. 2 is a side elevation of a portion of the club guiding mechanism, showing details of construction;

Fig. 3 is an enlarged view, partially in section, showing constructional details of a portion of the club holding mechanism;

Figs. 4 and 5 are, respectively, side and front elevations, with parts broken away, of another portion of the club guiding mechanism;

Figs. 6 to 10, inclusive, are side elevational views of the various parts which together form a new type universal joint used in connecting a golf club to the club guiding mechanism;

Fig. 11 is an enlarged perspective view, with parts broken away and parts in section, showing details in the construction of the machine locking and coin releasing mechanism;

Fig. 12 is a diagrammatic front elevation of a portion of the machine, and is included primarily to aid the reader in understanding the manner

in which the machine positively guides the travel of the golf club during the swing;

Fig. 13 is a fragmentary sectional view showing in detail a preferred manner of rotatably mounting the club guiding mechanism, and also showing its relation to the coin mechanism housing;

Fig. 14 is a plan view showing further details of part of the coin releasing mechanism; and

Figs. 15 and 16 are side and front views respectively, with parts in section, of an additional part of the coin releasing mechanism.

Fig. 17 is a rear plan view of the central portion of a plate which is a part of the guide carriage.

The embodiment of the invention illustrated includes an upright, inverted L type standard, designated as a whole by the numeral 20. This standard includes a base plate 21, drilled for attachment to a suitable base or platform.

Having one of its ends pivotally connected to the end of the horizontally projecting portion of this standard, is a supporting arm 22, which is firmly supported from its pivot point in various desired planes by means of an adjusting mechanism mounted near the upper end of said standard. This mechanism includes a threaded rod 23 disposed lengthwise immediately beneath this arm 22, and having one of its ends journaled in a journal bracket 24, preferably formed integrally on the upper end of the standard. The journaled end of this rod 23 extends through the bracket and carries a gear 25, which meshes with a hand wheel type gear 26, which is also suitably mounted on the standard 20. The means journaling the threaded rod 23 does not permit axial movement, but only rotative movement. An internally threaded collar 27 travels on the rod 23, and a link 28 has one of its ends pivotally connected to this collar, and its other end pivotally connected to the supporting arm 22 by means of an integral bracket 29 located on the under side thereof. When the hand wheel 26 is rotated in one direction, the threaded rod 23 is also rotated, and the consequent axial movement of the collar 27 along the rod 23 forces the supporting arm 22 to pivot in one direction about its pivot point. A reversal of the hand wheel 26 moves the arm 22 in the opposite direction. This is an adjustment to accommodate players of different height, and we therefore provide an indicator 30 rigidly attached to the arm 22, and a height scale 31 rigidly attached to the end of the support 20. The co-operation of these two quickly apprises a player when he has the arm 22 properly positioned for his own particular height.

Mounted rigidly near the free end of the supporting arm 22, and extending sidewise therefrom is a rigid extension arm 32 which rigidly supports an arcuate member designated as a whole by the numeral 33. The entire peripheral edge of this member 33 serves as a track for a guide roller in a manner described herein, and the member will therefore be hereinafter referred to as a track 33.

Rotatably mounted on the extreme outer end of the arm 22 in a plane perpendicular to the longitudinal axis thereof is a guide carriage designated as a whole by the numeral 34. This carriage includes an elongated plate 35 pivoted intermediate its ends at point 36 to the arm 22, as mentioned. A combination radial and thrust bearing 37 is used for mounting this entire carriage 34, as shown in Fig. 13, so that when the

carriage lies outside the vertical plane due to an adjustment of the arm 22, there is still very little bearing resistance to the free rotation or movement of the carriage. Since the constructional details of the bearing mounting are shown clearly in Fig. 13, it is believed that further description of this mounting is unnecessary.

Near one end, the plate 35 carries a counter-balancing weight 38, while on the other side of the pivot point 36, it carries a plate 39 positioned in a parallel spaced relation thereto by means of a plurality of identical spacer bars 40, certain ones of which rotatably mount guide rollers 41, 42, 43, and 44, all of which aid in guiding the longitudinal movement of a club holding arm 45 in the guide carriage 34.

The arm 45 has a straight shank portion 46 which is substantially square in cross section, and an arcuately curved portion 47. On the shank 46 are rotatably mounted guide rollers 48, 49, 50, and 51 which are adapted to roll on the adjacent surfaces of the parallel plates 35 and 39, and thus additionally guide the shank 46 during its longitudinal movement. It will be noted that the rollers 41 to 44 inclusive lie directly in the path of travel of the rollers 50 and 51, and thus serve to limit the longitudinal movement of the shank 46 in both directions.

As a means of normally maintaining the shank 46 at the inner end of its limited path of travel we provide a coil spring 52, one end of which is secured to an outwardly projecting pin 53 mounted on the plate 35, and the other end of which is secured to an outwardly projecting pin 54 carried by the shank 46. Longitudinal travel for the pin 54 is afforded by an elongated slot 55 cut in the plate 39.

The shank 46 carries an oppositely projecting pin 56 which in turn carries a ball bearing roller 57. A slot 58 in the plate 35 affords free longitudinal travel for the pin 56 as the shank 46 moves. This roller 57 is mounted in the same plane with the track 33, while the arm 32 which supports the track lies out side this plane.

With such a mechanical structure, it will be seen that when force is applied to the free end of the club supporting arm 45 to move it and the guide carriage 34 in a counterclockwise direction, the roller 57 contacts and rolls along the outer peripheral surface of the track 33, and the arc in which the track forces the roller to travel has a direct relation to the arc in which the roller 57, in turn, forces the free end of the arm 45 to travel (see Fig. 12). By varying the shape of the outer peripheral surface of the track, the arc in which a club 59 held by the free end of the arm 45 must travel during the back-swing, can definitely be determined. Likewise, since the roller 57 must travel on the inner peripheral surface of the track 33 during the down-stroke (or clockwise movement of the carriage 34) the changing of the shape of this surface will definitely determine the arc in which a club held by the arm 45 must travel during the down stroke.

To make sure that a player using the device take a full back swing, we provide a spring pressed pivotally mounted trigger 60 on the upper end of the track 33. The outer peripheral surface of this trigger 60 lies directly in the path of travel of the roller 57, and so long as a full back swing is taken, the roller 57 rolls smoothly over this trigger surface, and on to the inner peripheral surface of the track 33. The position of the roller 57 at the top of a full back

swing may be observed in carriage position C of Fig. 12 (dotted lines). In case a player begins his down swing before he has taken a proper complete back swing, the roller 57 presses down on the outer surface of the trigger 60 compressing spring 61, and the roller then hits the adjacent part 62 of the track, and the downward travel of the carriage and the club is stopped. This forces the player to the top of his backswing before he can take the down swing.

To assure that the roller 57 always travels up the outside of the track 33 during counterclockwise movement of the carriage (during the backswing), we provide a pointed trigger 63 which is pivotally mounted on the opposite end of the track 33, and is normally held in the solid line position shown in Fig. 2, by means of a spring 64, mounted as shown. In this position the tip end of the trigger lies inside the arc in which the axis of the roller 57 moves, so that the roller 57 must always move up the outside of the track 33. This trigger 63 has an additional function, however, and that is to present a slight resistance to the travel of the roller 57 as the roller approaches the end of the track during the downswing. When the roller 57 moves from the track proper on to the inner surface of the trigger, the trigger is forced to move to the position shown by the dotted lines in Fig. 2, and the tension of the spring 64 consequently tends to slightly slow the travel of the roller and of the carriage 34. This resistance to free travel is transmitted to the muscles of the player swinging the club 59, and his reaction is to use more wrist power to force the club head to continue its travel. By varying the length of the trigger 63, as well as the tension of the spring used, a player can be taught when to bring his wrist muscles into his swing, and can also be taught approximately how much wrist pressure should be used.

After the roller 57 leaves the tip end of the trigger 63, practically all resistance to the free rotation of the carriage 34 is removed, and that lack of resistance coupled with the momentum of the carriage and its counterweight, causes the player swinging the club to "follow through" on his swing, or in other words, to fully complete the swing of the club. We call attention to the fact that by curving the club holding arm 45 substantially as illustrated, the arm easily clears the head of the player, even though the carriage 34 moves through an arc of 180° or more from the position shown in Fig. 1, either during the backswing, or during the "follow through" on the downswing.

As a means of connecting a golf club to the free end of arm 45, we provide a unique type of universal joint, designated as a whole by numeral 65. This joint includes a sleeve 66 which is interiorly tapered to fit the tapered shaft of the club 59. In assembly, the club head is removed, the sleeve 66 is heated, and then slipped on to the club shaft to a point near the handle, where it shrinks to a tight fit. The sleeve has a thrust collar 67, a cylindrical bearing surface 68, and a reduced threaded end 69. The bore of a second sleeve 70 complementally receives the bearing surface 68, and the sleeve 70 is held in position on this bearing surface by an internally threaded thrust collar 71, which screws on the threaded end 69. This sleeve 70 has a pivot pin 72 projecting at right angles therefrom, adapted to receive a sleeve 73, one end of which is provided with an integral knurled collar 74 to facilitate screwing

this sleeve tightly into a socket 75 (Fig. 3) which is pivoted for movement in one plane only in the end of the arm 45 in the manner shown in Fig. 3. The sleeve 73 is held in position on the pivot pin 72 by means of a large headed screw 76 and a washer 77. This screw screws into the threaded end of the pin 72. After the universal joint has been assembled, as described, on the club shaft the sleeve 73 is simply screwed tightly into the socket 75 by use of the knurled collar 74. The socket 75 is permitted a pivotal movement of about 30° to allow for height adjustment of the machine, for slight variations in the angle at which different players hold their clubs with relation to the ground surface, and also to allow for the breaking of the wrists near the top of the backswing. This joint permits rotation of the club about its own longitudinal axis while also permitting a rotation of the club with relation to the arm 45 with the socket 75 as an axis. Thus a player can grasp the club in the usual manner, swing it back to the top of the back swing, take the full down swing and complete the "follow through" stroke, all without any appreciable resistance from the means connecting the club to the arm 45 and its carriage 34.

While the device thus far described is a complete operating unit in itself, in order to make it commercially practical, we definitely include, as a part of the invention to be used optionally, a coin released control mechanism.

This mechanism is located in a stationary housing 78 mounted on the end of the arm 22 (Figs. 1 and 13). The open front end of the housing fits closely against the inside surface of the rounded portion of the plate 35 as already shown in Fig. 13, so that this plate, while it turns in relation to the housing, actually serves as a closure for the housing. The housing 78 may also serve as a coin box, and the coins can be removed by simply unscrewing the pivot pin 36 and removing the entire assembled carriage 34 from the standard.

Inside the housing, a ratchet wheel 79 is rotatably mounted (Fig. 11). An arcuate leaf spring 80 contacts the teeth of the wheel and serves to prevent its free rotation except in one direction, and then only in response to positively applied force. A dog 81 mounted for reciprocal movement in a housing 82 is spring pressed by means of spring 83, to contact the ratchet wheel. The housing 82 screws into a threaded perforation 84 (Fig. 1) in the plate 35, so that the dog 81 moves about the axis 36 with the plate 35 as it rotates. On each backswing (counterclockwise movement) of the carriage, the dog 81 contacts a tooth of the wheel 79 and rotates it a distance equivalent to the spacing of the teeth, and against the tension of spring 80. On the downswing, however, the spring 80 holds the wheel against rotation, and the sloping face of the dog rides over the sloping face of the nearest tooth, and this is repeated with each complete swing of the club, thus gradually rotating the ratchet wheel.

Screwed into the back wall of the housing 78 is a lock pin housing 85, which reciprocably houses a lock pin 86 spring pressed toward the plate 35 by means of spring 87. The adjacent surface of the rounded central portion of the plate 35 is superficially slotted with an arcuate cam type slot 103 (Fig. 17) to receive the end of the pin 86, and to be thereby locked against counterclockwise rotative movement.

For retracting the lock pin 86 from its locked

position in the slot 103 in plate 35, we provide a lever 88 pivotally mounted intermediate its ends on a pivot pin 89, in such position that one of its ends moves in a plane to contact a projection 90 on the pin 86. Near the other end of the lever 88 is a hook-like portion 91 immediately adjacent the inner end of a coin chute 92 which extends through the wall of the housing 78. The housed portion of the coin chute includes a gravity or spring operated pivotally mounted dog 93 which lies directly in the path of travel of a coin in the chute. An interior lug 102 limits the pivotal movement of this dog 93 in one direction. Externally, the coin chute is provided with a coin insert opening 94, and a bar 95 adapted to be reciprocated in the chute 92 by means of a hand lever 96 (Fig. 1), pivotally mounted on the arm 22.

To fully understand the operation of this control mechanism, it should be noted from Fig. 11, that the ratchet wheel 79 is provided with a through coin slot 97, which, when the wheel is rotated to the proper position, exactly aligns with a coin slot (not visible in the drawings) in the bottom of the coin chute 92 near its end.

The extreme outer end of the lever 88 terminates in a lug 98, which carries a downwardly projecting spring pressed dog 99 (Figs. 15 and 16) mounted in a small housing 100, which screws into the underside of the lug 98. This dog co-operates with a cam 101 formed on the upper surface of the ratchet wheel 79, the dog and cam being sufficiently wide radially that the dog stays in contact with the cam during the travel of the lever 88 from its solid line, or locked position in Fig. 14, to its dotted line, or unlocked position, even though the pivotal axes of the wheel 79 and of the lever 88 are spaced apart.

As illustrated in Fig. 11, the control mechanism has almost reached its locked position, and the pin 86 by its penetration into its arcuate slot in the plate 35, prevents movement of the carriage 34 counterclockwise about its axis. To release the carriage so that a player may use the device, a coin of the proper denomination is inserted into the chute, the lever 96 is pulled forward causing the bar 95 to contact and force the coin toward the inner end of the chute. As the coin approaches the inner end of the chute, the edge of the coin first forces the dog 93 out of its way, and then contacts part 91 of the lever 88, forcing this lever to pivot about its axis 89, and to simultaneously retract the lock pin 86 from its arcuate slot 103 in the plate 35. During this movement the dog 99 contacts the cam 101 on the wheel 79 and, if the coin is of the proper denomination, rotates that wheel a distance equivalent to the spacing of the teeth, thereby moving the slot 97 away from the end of the chute 92, and preventing the newly inserted coin from falling through the slot. Immediately after the coin passes the dog 93, that dog moves back to its normal position in the chute against the lug 102 and prevents the coin from backing up. The coin wedged between the dog 93 and the end 91 of the lever 88, and resting on the upper surface of ratchet wheel 79, thus prevents the lever from returning to its normal locked position. The lever, likewise, holds the lock pin 86 in retracted position, and the device is unlocked and ready for use.

If the coin inserted in the coin chute is smaller in diameter than a coin of the proper denomination, then the lever 88 is not moved far enough

to completely retract the pin 86 from its recess in the plate 35, nor is the ratchet wheel 79 rotated sufficiently for the next adjacent tooth to pass the spring 80. Hence the ratchet wheel 79 returns toward its former position, and the smaller coin drops through the slot 97 without unlocking the device, and all parts of the mechanism return to their former locked positions.

The slot 97 serves as a means of again automatically locking the device after a predetermined number of practice strokes have been taken. As previously mentioned it is so positioned that it moves into alignment with the slot in the bottom of the coin chute 92 after the ratchet wheel has made one complete revolution. When the two slots are aligned, the coin drops through slot 97 into the lower part of the housing. This permits the lever 88 and the lock pin 86 to return to their relative locked positions, at which time further use of the machine is prevented until another coin is inserted in the chute and the cycle repeated.

From this description it should be clearly understood how the device accomplishes the objects mentioned above. The adjustment of the arm 22 about its pivot point definitely changes the position of the carriage axis 36 with relation to the horizontal. The changing of this axis 36 naturally determines the respective planes in which the guide carriage, as well as the end of the arm 45, must travel during the rotation of the carriage about its axis. The changing of the plane in which the outer end of the arm 45 must travel, in turn changes the slant of the respective planes in which the player's hands and the club head must travel during their movement by the player in taking his swing. The adjustment of the arm 22 then, definitely determines the proper planes of travel for the player's hands and the clubhead, with relation to the player's height.

On the other hand the peripheral shape of the guide track 33 definitely determines the paths in which the club head and the player's hands must travel in their respective planes. These two guiding forces, combined with the universal joint mounting and the pivotal socket 15 force the proper pronation of the hands and club during the backswing, the proper pivoting of the body, and above all assure that the club and the player's hands coincide with the line of intersection of the respective planes in which the two travel, at the very top of the backswing. In this position an imaginary extension of the longitudinal axis of the club would pass directly through the point toward which the player intends to shoot the golf ball.

While we have described and illustrated only a single embodiment of the invention, we are aware it may be embodied in other forms, and we do not wish to be limited except by the prior art and by the scope of the appended claims.

We claim:

1. In a device for guiding a golf club through a predetermined path during its swing by a player, a guide track; a club guiding mechanism one end of which is rotatably mounted to move in a plane parallel to and immediately adjacent the plane in which said guide track lies, and another part of which is movable radially with relation to the rotational axis of the first mentioned end; and a roller rotatably mounted on the radially movable portion of said club guiding mechanism and adapted to roll on said guide track as the entire mechanism rotates about its

axis, the contour of the guide track being adapted to predetermine the path in which the free end of said club guiding mechanism travels during at least a portion of the rotational movement of said mechanism.

2. In a device for guiding a golf club through a predetermined path during its swing by a player, a guide track; a club guiding mechanism one end of which is rotatably mounted to move in a plane parallel to and immediately adjacent the plane in which said guide track lies, and another part of which is movable radially with relation to the rotational axis of the first mentioned end, said rotational axis being movable into different positions with relation to the horizontal to change the plane in which said club guiding mechanism moves during its rotation; and a roller rotatably mounted on the radially movable portion of said club guiding mechanism and adapted to roll on said guide track as the entire mechanism rotates about its axis, the contour of the guide track being adapted to predetermine the path in which the free end of said club guiding mechanism travels during at least a portion of the rotational movement of said mechanism.

3. In a device for guiding a golf club through a predetermined path during its swing by a player, a guide track; a club guiding mechanism one end of which is rotatably mounted to move in a plane parallel to and immediately adjacent the plane in which said guide track lies, and another part of which is movable radially with relation to the rotational axis of the first mentioned end; a roller rotatably mounted on the radially movable portion of said club guiding mechanism and adapted to roll on said guide track as the entire mechanism rotates about its axis, the contour of the guide track being adapted to predetermine the path in which the free end of said club guiding mechanism travels during at least a portion of the rotational movement of the mechanism; means for locking the club guiding mechanism against rotation about its axis; and coin operated means for releasing said locking means.

4. In a device for guiding a golf club through a predetermined path during its swing by a player, a guide track; a club guiding mechanism one end of which is rotatably mounted to move in a plane parallel to and immediately adjacent the plane in which said guide track lies, and another part of which is movable radially with relation to the rotational axis of the first mentioned end; a roller rotatably mounted on the radially movable portion of said club guiding mechanism and adapted to roll on said guide track as the entire mechanism rotates about its axis, the contour of said guide track being adapted to predetermine the path in which the free end of said club guiding mechanism travels during at least a portion of the rotational movement of said mechanism; and means for changing the position of the rotational axis of said club guiding mechanism with relation to the horizontal.

5. In a device for guiding a golf club through a predetermined path during its swing by a player, the combination of, a club guiding arm; means at the free end of said arm for connecting a golf club; a rotatably mounted guide carriage supporting the other end of said arm for movement toward and away from the rotational axis of the carriage, said arm also movable in an arcuate path to any one of a plurality of predetermined planes as said guide carriage rotates

about its axis; means for changing the position of the rotational axis of said guide carriage with relation to the horizontal to predetermine the particular plane in which said club guiding arm must move when the guide carriage rotates; a guide roller mounted on said club guiding arm with rotational axis parallel to the rotational axis of said carriage; and a concavo-convex guide on which said roller moves during at least a part of the travel of said club guiding arm, the contour of said track being adapted to predetermine the arcuate path in which the club carrying end of said club guiding arm travels in its predetermined plane.

15 6. A device for guiding a golf club through a predetermined path during its swing by a player comprising: a guide carriage supporting arm mounted for adjustment in a substantially vertical plane; a guide carriage mounted on an end of said supporting arm for rotation in various planes all normal to the plane in which the supporting arm moves; a club guiding arm having one end mounted in said carriage for longitudinal movement toward and away from the rotational axis of said carriage; a guide roller mounted on said club guiding arm and rotatable about an axis parallel to rotational axis of said carriage; an arcuate guide track also supported on said guide carriage supporting arm, and in the same plane in which said roller rotates; and a universal joint for connecting the shaft of a club to the free end of said club guiding arm.

35 7. A device for guiding a golf club through a predetermined path during its swing by a player comprising: a guide carriage supporting arm mounted for adjustment in a substantially vertical plane; a guide carriage mounted on an end of said supporting arm for rotation in various planes all normal to the plane in which the supporting arm moves; a club guiding arm having one end mounted in said carriage for longitudinal movement toward and away from the rotational axis of said carriage; a guide roller mounted on the club guiding arm and rotatable about an axis parallel to the rotational axis of said carriage; an arcuate guide track also supported on said guide carriage supporting arm, and in the same plane in which said roller rotates; a universal joint for connecting the shaft of a golf club to the free end of said club guiding arm; means for locking the guide carriage against movement about its axis; and coin operated means for releasing said locking means.

55 8. A device for guiding a golf club through a predetermined path during its swing by a player, comprising: a supporting standard; a guide carriage supporting arm having one of its ends pivotally mounted on said standard for adjustment in a substantially vertical plane; a guide carriage mounted on the free end of said supporting arm its rotational axis being at right angles to the pivotal axis of said supporting arm; a counterweight for said guide carriage; a club guiding arm carried by said guide carriage and movable toward and away from the axis thereof, one end of said club guiding arm projecting outward at an angle to the plane in which the carriage rotates; a guide roller mounted on said club guiding arm for rotation about an axis parallel to the rotational axis of the carriage; a concavo-convex guide track rigidly supported on the guide carriage supporting arm in the same plane in which said roller rotates and in which the roller travels as the guide carriage rotates; and a universal joint for connecting the shaft of a golf

club to the free end of said club guiding arm which projects outwardly from said guide carriage.

9. A device for guiding a golf club through a predetermined path during its swing by a player, comprising: a supporting standard; a guide carriage supporting arm having one of its ends pivotally mounted on said standard for adjustment in a substantially vertical plane; a guide carriage mounted on the free end of said supporting arm, its rotational axis being at right angles to the pivotal axis of said supporting arm; a counter-weight for said guide carriage; a club guiding arm carried by said carriage and movable toward and away from the axis thereof, one end of said club guiding arm projecting outward at an angle to the plane in which the carriage rotates; a guide mounted on said guiding arm for rotation about an axis parallel to the rotational axis of the carriage; a concavo-convex guide track rigidly supported on the guide carriage supporting arm in the same plane in which said roller rotates and in which the roller travels as the guide carriage rotates; a universal joint for connecting the shaft of a golf club to the free end of said golf club guiding arm which projects outwardly from said guide carriage; means for locking the guide carriage against movement about its axis; and coin operated means for releasing said locking means.

10. A device for guiding a golf club through a predetermined path during its swing by a player comprising: a supporting standard; a guide carriage supporting arm having one of its ends pivotally mounted on said standard for movement in a substantially vertical plane; means for adjusting the position of said supporting arm with relation to said standard; co-operating means on the standard and the supporting arm for indicat-

ing the degree that the arm changes position with relation to the standard; a guide carriage rotatably mounted on the free end of said supporting arm; a rigid club guiding arm having one end mounted in said carriage for radial movement with relation to the carriage axis, and having its other end arcuately bent and adapted for connection to the shaft of a golf club; a guide roller mounted on said club guiding arm and rotatable on an axis parallel to the carriage axis; an arcuate guide track also supported from said guide carriage supporting arm, and lying in the plane in which said roller rotates, said roller being adapted to roll on said track as the club carrying arm and its carriage move around the carriage axis, said track and roller being adapted to predetermine the path in which the club travels.

11. In a device for guiding a golf club through a predetermined path during its swing by a player, which device includes a rotatably mounted club guiding and holding mechanism and a track for predetermining the path of travel of the club holding portion of said mechanism during rotation of the mechanism about its axis, means for connecting the club holding portion of said mechanism to a golf club comprising: a threaded socket mounted for limited pivotal movement in a plane radial to the rotational axis of the club guiding and holding mechanism; and a universal joint one portion of which is securely attached to the shaft of the club, and another portion of which is adapted to screw into said socket and to afford free movement of the club about its own longitudinal axis and about an axis normal thereto and extending radially with relation to the pivotal axis of said socket.
